(57) **CLAIM**

The ornamental design for a push-pull wheeled luggage, as shown and described.

DESCRIPTION

FIG. 1 is a side view of the push-pull wheeled luggage, which is tilted backward when placed on a flat surface. A user holding a handle of the push-pull wheeled luggage, shown in broken lines, is merely illustrative and does not form any part of the claimed design.

FIG. 2 is a bottom view of the push-pull wheeled luggage with a swingable wheel and a pair of fixed wheels.

FIG. 3 is a laid-down side view of the push-pull wheeled luggage; and,

FIG. 4 is an enlarged view of the swingable wheel.
